STOKER CONVEYER

Howard P. Anderson, Erie, Pa., assignor to The Standard Stoker Company, Inc., (1922), a corporation of Delaware

Application July 18, 1931, Serial No. 551,605
Renewed February 6, 1937

19 Claims. (Cl. 198—15)

My invention relates to stokers particularly those applicable to locomotives, and has for its main object the provision of a stoker conveyer formed of flexibly connected sections wherein the forward section is flexibly attached to the firebox for fore and aft movement with reference thereto.

Another object of my invention resides in the provision of an improved locomotive stoker conveyer comprising a conduit which is supported 10 solely by the locomotive and is flexibly connected at its rearward end with a conveyer leading forwardly from the tender, and at its forward end being flexibly connected with respect to said backhead, whereby the rearward end of said conduit 15 section may swing upwardly or downwardly during operation of the locomotive and tender without imparting stresses to the backhead.

Other objects of the invention residing in the construction of the individual elements and their 20 relation one with another will be apparent from the following description read in connection with the accompanying drawing, wherein

Fig. 1 is a central longitudinal section through a locomotive and its tender with the stoker conveyer of this invention shown applied thereon with some parts broken away and others in section;

Fig. 2 is a transverse vertical sectional view on the irregular section line 2—2 of Fig. 1; and 30 Fig. 3 is a plan section on the line 3—3 of Figure 1 with the fuel advancing means removed.

On the drawing the locomotive is represented at A and the tender therefor at B. Both are of conventional construction and coupled together 35 by the usual coupler and drawbar connections, not shown, to permit articulation when passing over curving track or for other purposes.

10 represents the locomotive firebox having a backwall 11 with a firing opening therein at 13, 40 which opening is located above the deck 14 of the cab 15. 16 represents the tender deck or floor; 17 the fuel bunker and 18 the tender base or frame. Fuel is transferred from the fuel bunker 17 to the firing opening 13 by a stoker 45 conveyer system comprising a rearward or trough section 19, an intermediate tubular section 20 and a forward or riser housing section 21.

The trough section 19 may be of any well known form in the art and is rigidly mounted 50 on the frame 18 in any desired manner. The trough carries at its forward end a spherical shell member 22 which receives the vertically split spherical clamp or joint member 23 which forms the rearward end portion of the intermediate conduit 20. The clamp member 23 has a convex

spherical end face 24 formed on its forward end. This spherical end is seated in the flaring spherical extension 25 of the tubular conduit portion 26 of the intermediate conduit 20. The portion 26 is rigidly fixed to the clamp member 23 by 5 spring pressed latches 27, 27a pivotally mounted on the pintles 28, 28a in the lugs 29, 29a. The latches 27, 27a engage prongs 30, 30a of the clamp member 23 formed by grooves or recesses as at 31. The latches are held in engagement 10 with the prongs by springs 32, 32a.

The forward end of the intermediate conduit 20 carries the ball 33 which is received in the horizontally split spherical seat portion 34 of the forward or riser housing section 21. Thus the 15 intermediate section 20 is flexibly secured at its ends to the rearward and forward conveyer sections. Preferably, the trough and intermediate conveyer sections including the ball 33 are disposed beneath the decks 14 and 16, in order to 20 place all laterally swinging parts of the conveyer system beneath the cab 15.

The riser housing 21 extends forwardly and upwardly from its spherical portion 34 through the deck 14 to a point adjacent the backwall 11 above the lower marginal edge of the opening 13. The upper end of this riser is hinged to the transversely extending shaft 35 which extends through and beyond the riser sidewalls 36, 36a and is carried in a ring-like bracket or section 37. This 25 bracket bounds the firing opening 13 and is rigidly secured to the firebox backwall. In its lower portion there is formed integrally the distributor plate 38 which projects forwardly through the opening 13 into the firebox 10. This plate is integral with the lower cross bar of the ring 37 and it may be of any suitable form for deflecting and distributing fuel over the firebox in cooperation with a distributor nozzle such as the one 30 represented at 39. The mouth portion 40 of the 35 riser is disposed above the nozzle to discharge the fuel forward thereof on to the distributor plate 38. Rearwardly extending vertically disposed plates or flanges 41 and 41a are formed integrally with the ring 37 to prevent loss of fuel from the mouth portion 40 of the riser. Any conveying means like the screw 43 may be mounted within the conveyer system for advancing the fuel there-through and if desired, the screw may be provided with a section extending within the forward 40 or riser conduit section.

The bottom wall 42 of the riser section near its lower end portion beneath the deck 14 has lugs 43 formed therewith which carry the transverse shaft 44 on each end of which there is mounted 50 55

a flanged roller as at 45. The rollers 45 engage longitudinally extending parallel arcuate shaped seats or tracks 46, detachably mounted on the bracket 47 fixed to the backwall 11. The tracks 46 may be held to the bracket by any suitable fastening means, such as by the rivets 48. The radius of each track 46 is swung from the axis of the transverse shaft 35, hence the riser housing 21 can move fore and aft with reference to the 10 firebox about the shaft 35.

Thus it will be seen when the locomotive and its tender are passing over curving track and the longitudinal distance between the two increases the riser housing 21 will rise on the tracks 46 15 moving in an arc from the axis of the hinge or shaft 35 thereby increasing the angle of inclination of the intermediate conduit section 20, which is of fixed or unvarying length, having the effect of straightening out or lengthening the conveyer 20 to provide for the increased longitudinal distance between the conveyer parts on the locomotive and tender; and at the same time, the required lateral movement between the riser section on the locomotive and the trough section on the tender is 25 provided by lateral movement of the intermediate section by reason of its universal connections with the end sections.

Likewise the stoker conveyer of this invention responds to any other movement of the locomotive and its tender. For example, in making up trains the coupling member between the locomotive and tender may be compressed, in effect, shortening the distance between the parts. In response to this movement the inclination of the 30 intermediate conduit 20 will be lessened and the riser 21 will roll or slide downwardly on the tracks 46 moving closer to the backhead. When the coupling connection assumes its normal position the riser housing rises to its operative or 35 normal position as shown on the drawing. Any vertical movement between the locomotive and tender is permitted by the flexible arrangement of the intermediate conduit 20 with the end sections, and should the vertical movement be such 40 as to increase the longitudinal distance between the parts this is then compensated for by fore and aft movement of the riser 21 on the tracks 46. In event it is desired to disconnect the 45 tender from the locomotive and hence the trough 50 19 from the intermediate and forward conduit sections, this can be done simply by compressing the springs 32, 32a of the latches 27, 27a thereby disengaging the intermediate conduit tubular portion 26 with the spherical clamp member 23.

The invention provides a simple, cheaply constructed and durable form of stoker conveyer free from telescoping or extensible parts and one wherein the fuel may be conveyed from the trough 19 to the firing opening 13 through an 60 enclosed passage having no openings therein to cause loss of fuel.

While only one embodiment of my invention is shown, it may be employed in various forms within the scope of the appended claims.

65 I claim:

1. In combination, a firebox backwall having a firing opening therein, an upwardly extending conduit section delivering to said opening, a hinge having its axis substantially parallel with said 70 backwall and connecting the forward end of said conduit with said backwall, said conduit adjacent its fuel receiving end carrying supporting means, and an arcuate track for said supporting means permitting swinging movement of said conduit 75 about the axis of said hinge.

2. In combination with a firebox backwall having an opening therein, a bracket extending from said backwall and carrying an arcuate shaped track, and an upwardly extending stoker conduit section in communication with said opening and at its upper end hinged above said track to said backwall, the axis of said hinge being substantially parallel to said backwall and permitting only swinging fore and aft movement with reference thereto, said conduit at its lower end portion carrying a roller engaging said track. 10

3. In combination with a firebox backwall having an opening therein, a bracket extending from said backwall and carrying a pair of longitudinally extending parallel arcuate shaped tracks, 15 and an upwardly extending stoker conduit section in communication with said opening and at its upper end hinged above said tracks to said backwall, the axis of said hinge being substantially parallel to said backwall and permitting only swinging fore and aft movement with reference thereto, said conduit at its lower end portion carrying a pair of laterally spaced rollers 20 engaging said tracks.

4. In combination with a firebox backwall having a firing opening therein, a ring member bounding said firing opening and carrying a shaft mounted parallel with the backwall, a stoker conduit section at its forward end pivotally mounted on said shaft and arranged to discharge 30 fuel through said ring into said opening, said conduit adjacent its rearward end portion on its underside having supporting means arranged therewith, and a bracket extending from said backwall with a portion thereof engaging said 35 supporting means, said means and bracket arranged to permit swinging fore and aft movement of said conduit with reference to the backwall about the axis of said shaft. 40

5. In combination with a locomotive having a 40 firing opening in its backwall and a tender coupled to said locomotive, a stoker conveyer comprising a rearward conduit section mounted rigidly on the tender with reference to longitudinal movement thereof, an upwardly extending conduit section carried solely by said locomotive and communicating with the firing opening, said last named conduit section at its upper forward end being mounted for pivotal movement, and an intermediate conduit of constant length between 50 said rearward conduit section and said upwardly extending conduit section, said intermediate conduit at its rearward end being universally connected to the forward end of said rear conduit section and at its forward end being universally 55 connected to the lower rearward end of said upwardly extending conduit.

6. In combination with a locomotive provided with a firebox backwall having an opening therein, an upwardly extending stoker riser conduit in communication with said opening and being pivotally attached to said backwall for swinging fore and aft movement only with reference thereto, and means carried by the locomotive for supporting the overhanging weight of said riser conduit, 60 said means including an arcuate track arranged to permit arcuate sliding movement thereover by said conduit.

7. In combination with an articulated locomotive and tender, the former being provided with a 70 firebox having a backwall and the latter having a fuel bin, means for transferring fuel from said bin to said firebox comprising a conveyer of constant length leading forwardly from the tender and an upwardly extending elevating conveyer 75

supported solely on said locomotive and communicating with said conveyer conduit, said elevating conveyer including a short section rigid with said backwall and a conduit section at its upper forward end flexibly related with said section and at its rearward lower end flexibly connected with the forward end of said conveyer conduit whereby the forward end of said conveyer conduit and the lower end of said conduit section may move upwardly in a rearward direction and downwardly in a forward direction during operation of the locomotive and tender.

8. In combination with an articulated locomotive and tender, the former being provided with a firebox having a backwall and the latter having a fuel bin, means for transferring fuel from said bin to said firebox comprising a trough conduit rigidly mounted on said tender beneath said fuel bin, an upwardly and forwardly extending elevating conduit supported solely on said locomotive and at its forward end being flexibly related with reference to the firebox backhead, and an intermediate conduit of constant length between said trough conduit and said elevating conduit, said intermediate conduit at its forward end flexibly connected with the lower rearward end of said elevating conduit and at its rearward end flexibly connected with the forward end of said trough conduit.

30 9. In a locomotive having a firebox provided with a backhead, a conveyer for delivering fuel to said firebox comprising an upwardly extending conduit section carried solely by said locomotive and at its upper forward end being mounted for pivotal movement, a support for said conduit carried by said locomotive rearward of said backhead, and a conduit flexibly connected at its forward end with the rearward lower end of said upwardly extending conduit whereby the rearward lower end of said upwardly extending conduit and the forward end of said last named conduit may move upwardly in a rearward direction and downwardly in a forward direction.

10. In combination with an intercoupled locomotive and tender, the former having a firebox and the latter a fuel bin, a conduit system extending between the firebox of the locomotive and fuel bin of the tender, said conduit system including a pair of rigid conduit sections each being of constant length between its ends, means at the adjacent ends of said sections providing a flexible joint therebetween, one section of said conduit system being flexibly mounted on the locomotive and the other section of said conduit system being flexibly mounted on the tender, said conduit system being of constant length between the remote ends thereof, and means for restraining the aforesaid sections of said conduit system against movement longitudinally with reference to the respective vehicle upon which each is mounted.

11. In combination with a locomotive including a boiler firebox provided with a backwall having a firing opening therein, a feed conduit for delivering fuel to said opening, means hingedly mounting the delivery end of said feed conduit with said backwall, and means on said locomotive for supporting the conduit and movable with the conduit in an arc swung from the axis of said first named means.

12. In an intercoupled locomotive and tender, a tubular conduit having a hinged joint at its delivery end with a conveyer member on the locomotive and a ball and socket joint at its receiving end with a conduit section on the tender whereby

said tubular conduit is vertically supported on both vehicles, said tubular conduit being provided with a bend intermediate its ends, and additional means for supporting said tubular conduit at the bend therein, said additional supporting means permitting movement of said tubular conduit about said hinged joint. 5

13. In an intercoupled locomotive and tender, a bent conveyer conduit flexibly connected at its delivery end to the backhead of the locomotive and having its receiving end mounted on the tender whereby the conduit is vertically supported on both vehicles, a bracket secured to the lower part of the backhead beneath said flexible connection, and additional means for supporting said conduit on the locomotive including a member interposed between said bracket and conduit at the bend in the latter.

14. In an intercoupled locomotive and tender, the former having a backwall, a conveyer conduit comprising a section mounted at its delivery end on the backwall of the locomotive and a section having its receiving end mounted on the tender whereby said conduit is vertically supported on both vehicles, means at the delivery end of the first named section providing a hinge connection of such section with respect to said locomotive backwall, and additional means on said locomotive for supporting said first named section and being movable therewith in an arc swung from 30 the axis of said first named means.

15. In an intercoupled locomotive and tender, the former having a backwall, a conveyer conduit extending between the locomotive and tender comprising a section at its forward end flexibly suspended from said backwall, and a section at its forward end flexibly related with the rearward end of the first named section for angular movement with respect thereto, said second named section rearward of its forward end being 40 flexibly supported on the tender whereby said conveyer conduit is vertically supported on both vehicles, and means on the locomotive forming an additional support for the first named section rearward of its forward end, said means permitting swinging movement of the first named section in a vertical plane. 35

16. In an intercoupled locomotive and tender, the former having a backwall, a conveyer conduit extending between the locomotive and tender comprising a section at its forward end flexibly related with said backwall for movement about a transversely extending horizontal axis only, and a section at its rearward end flexibly supported on the tender and at its forward end being flexibly related with the rearward end of the first named section, and means intermediate the ends of said conveyer conduit forming a support for the first named section. 55

17. In an intercoupled locomotive and tender, the former having a backwall, a conveyer conduit extending between the locomotive and tender comprising a forward section and a rearward section, means carried by the locomotive backwall forming a support for the forward end of said forward section, said forward section being only movable about a horizontal axis extending transversely of the locomotive rearward of said backwall, said rearward section at its rearward end being flexibly supported on the tender and 70 at its forward end being flexibly related with the rearward end of said forward section, and means intermediate the ends of said conveyer conduit forming a support for the forward section. 60

18. In an intercoupled locomotive and tender, a conveyer of constant length extending between the locomotive and tender, one end of said conveyer being flexibly supported on one of said vehicles and having an unvarying longitudinal relation therewith, the opposite end of said conveyer being disposed on the other of said intercoupled vehicles, and means for supporting the last named end of said conveyer on such vehicle, said means including a member pivotally supported on such vehicle to swing on a horizontal transverse axis, the last named end of said conveyer being flexibly supported on said member.
19. In an intercoupled locomotive and tender, a conveyer of constant length extending between

the locomotive and tender, one end of said conveyer being flexibly supported on one of said vehicles and having an unvarying longitudinal relation therewith, the opposite end of said conveyer being disposed on the other of said intercoupled vehicles, and means for supporting the last named end of said conveyer on such vehicle, said means including a member pivotally supported on such vehicle to swing on a horizontal transverse axis, the last named end of said conveyer being pivotally supported on said member for movement about vertical and transverse horizontal axes with respect to said member. 5 10

HOWARD P. ANDERSON. 15
